DESIGN FOR A PHOTOGRAPHIC PRINTER

Francis K. Moore, Chicago, Ill., assignor to Albert
Specialty Company, Chicago, Ill., a partnership

Application August 7, 1939, Serial No. 86,490

Term of patent 3½ years

To all whom it may concern:

Be it known that I, Francis K. Moore, a citizen of the United States, residing at Chicago, in the county of Cook and State of Illinois, have invented a new, original, and ornamental Design for a Photographic Printer, of which the following is a specification, reference being had to the accompanying drawing forming a part thereof.

In the drawing:

The rear and side of the photographic printer, opposite to the front and side, respectively, shown in the drawing, are substantially plain.

I claim:

The ornamental design for a photographic printer, as shown and described.

FRANCIS K. MOORE.
